UNITED STATES PATENT OFFICE.

HERMAN G. FISCHER AND PETER P. MUSKET, OF CHICAGO, ILLINOIS.

PHYSICIAN'S ELECTRICAL-APPLIANCE CONTROL.

1,260,354.

Specification of Letters Patent. Patented Mar. 26, 1918.

Application filed January 11, 1915. Serial No. 1,391.

To all whom it may concern:

Be it known that we, HERMAN G. FISCHER, a citizen of the United States, residing in Chicago, in the county of Cook and State of Illinois, and PETER P. MUSKET, a citizen of the United States, residing at Chicago, in the county of Cook and State of Illinois, have invented a new and useful Improvement in Physicians' Electrical-Appliance Controls, of which the following is a specification.

Our invention relates to physicians' electrical appliances and has for its object broadly the provision of an apparatus adapted to supply proper electric charges to vacuum electrodes, X-ray tubes, sinusoidal apparatus, diagnostic apparatus, cautery apparatus, and other implements and appliances of like nature.

A further object of the invention is the provision of such an apparatus provided with a Tesla coil receiving charging current through proper transforming apparatus, means being provided to accurately, positively and directly vary and control the charge received by the Tesla coil, and to provide an efficient and improved control for the sinusoidal, cautery and diagnostic circuits, such control being so constructed and arranged that it will be substantially impossible to deliver improper or dangerous charges to these circuits.

Numerous other objects and advantages will be apparent from the following description when considered in connection with the accompanying drawing, which illustrates diagrammatically a preferred arrangement embodying my invention.

Two main line or service wires 1 and 2, which may be considered a source of electrical energy, connect at one side of a cut-out switch 3 to suitable binding posts or terminals 4 and 5. From the terminal 6 at the other side, a wire 7 leads to one end of a primary coil 8 on a transformer 9. A wire 10 leads from the other end of this coil to a coil 11 about a reactance device 12. From various points in this coil, wires 13, 14 and 15 lead to terminals 16, 17 and 18. The reactance device 12 in the present instance is a soft iron core adapted when interrupted current is delivered to the circuit to interpose reactance in amount proportional to the number of turns in the coil 11; that is to say, the number of effective turns in the coil 11 which depends upon which terminal 16, 17 or 18 is connected with the other service wire to complete what may be termed the primary circuit in the apparatus. Connection is made from any one of the three terminals 16, 17 or 18 with a terminal 19 of the switch 3 when the switch is in closed position with the service wire 1 by a wire 21 connected to the terminal 19 and to a movable arm 22 adapted to contact in its movement with any one of the three terminals 16, 17 or 18, suitable stops 23 being provided to limit the movement of this arm. In the transformer 9 two secondary coils or series of coils generally designated at 24 and 25 are provided, one of which, the coil 25, being adapted to supply energy to the X-ray and vacuum electrodes, and the other, 24, to the cautery, diagnostic, and sinusoidal apparatus, as will be later described. A wire 26 leads from one end of the coil 25 to one side 27 of an interrupter 28, and a wire 29 leads from the other end of the coil 25 to the other side 31 of this interrupter. The interrupter 27 may have any preferred construction adapted to give the charge high and rapidly variable potential. In the present instance it is provided with a spark gap 32, which must be broken down to permit flowing of the current. A Tesla coil generally indicated at 33, and a condenser generally indicated at 34, are connected in series with each other and in shunt to the interrupter with the wires 26 and 29 of the secondary coil 25. This connection comprises a wire 35 leading from the side 28 of the interrupter to one side 36 of the condenser. A wire 37 leads from the condenser 34 to one end of a coil 38 disposed about a reactance imposing device 39. The coil 38 is tapped in at a plurality of turns, four in the present instance 41, 42, 43 and 44. Wires 45, 46, 47 and 48 connect these sets of turns respectively to buttons or terminals 49, 51, 52 and 53 adapted to be engaged by a movable arm 54 which is connected always by a wire 55 with one terminal 56 of the primary coil 57 of the Tesla coil 33. The other terminal 58 of this coil is connected through the wire 59 and wire 29 with the other side 31 of the interrupter 27. The reactance imposing device 39 and its control is thus interposed in the circuit directly connected to the Tesla coil and its control over the charge is directly felt. Movement of the arm 54 from one button 49, 51, 52 and 53 to another will interpose a different amount of reactance and

will correspondingly change the charge from the condenser 34 to the Tesla coil. The position of the arm shown on the drawing in engagement with the button 53 which is connected to the end of the coil 38, remote from the end of the coil connected to the wire 37, interposes the maximum amount of reactance provided in the present structure, and its movement toward the right in the figure cuts out a portion of this reactance until it reaches the button 49 interposing the least reactance.

A further control of this charge is effected through the condenser itself, this condenser being of the multiple order, having three outlet terminals 61, 62 and 63, the terminal 62 being connected to two terminals 64 and 65 by a wire 66, and the terminal 63 being connected to a terminal 67 by a wire 68. A movable arm 69 is connected by a wire 71 with the terminal 61 and it is to this wire that the wire 37 is connected. The portion of the condenser controlled by the terminal 61 is therefore always in the Tesla coil charging circuit. The portion connected by the wire 62 may be added by moving the arm 69 onto the contact 64 and the portion controlled by the terminal 63 may then be added by moving the arm on to the contact 65, which movement, by reason of the arrangement of the contacts 65 and 67, causes the arm 69 to engage the contact 67 also. The contacts 65 and 67 are arranged in line with the pivotal axis of the arm 69 and the contact 64 is off this alignment. Three separate devices are therefore provided for controlling the charge to the Tesla coil. The first, the reactance device 12, the second, the reactance device 39, and the third, the control just described for the multiple condenser. The reactance device 12 is not nearly so direct in its influence on the Tesla coil as is the reactance device 39, which is positioned between the interrupter 27 and the Tesla coil itself.

We are aware that prior to our invention reactance devices have been interposed between the interrupter and the service wires, but by reason of the remote control such devices have exercised their effect has not been all that could be desired, for the condenser being located between the reactance device and the Tesla coil and connected to the Tesla coil by a circuit over which there was no direct control, has prevented in large part the desired delicate control of the charge which my present arrangement provides.

The X-ray apparatus generally designated at 72, by dotted lines, is adapted to have one end connected to the center 73 of the Tesla coil which is connected by a wire 74 with the terminal 56 and which constitutes the active pole in the X-ray circuit.

The other end of the X-ray device is connected with an inactive pole 75, in turn connected by a wire 76 with the terminal 56 of the Tesla coil 33. A vacuum electrode indicated in dotted lines at 77 on the drawing, may be connected by a wire 78 with the center 73 of the Tesla coil in accordance with the usual custom.

Further description of the means of connecting the X-ray apparatus and the vacuum electrodes is not thought to be necessary, as these devices themselves form no part of our present invention. They are, however, indicated on the drawing to show how the circuits supplying proper charges to them are arranged in the present embodiment of our invention.

The other secondary coil 24 is preferably constructed of a series of coils as follows: At the forward end a large number of turns form a coil 79. The coil 79 may be of wire of any desired resistance. Following these coils are a series of coils (eleven) in the present instance indicated by light lines 82 of low resistance, the lowest possible resistance being desirable. Following this in series and in series with the coils 82 is a series of eight coils 83 which may have any desired resistance. These coils are all connected in series with each other and each have an end connected with a series of twenty terminals arranged on the circumference of a circle and numbered consecutively 1¹ to 20¹, in actual practice these terminals being numbered 1 to 20 for convenience. The connection between the coils and these terminals is made by wires 84 and 85, the wires 84 (those indicated by heavy lines) having any desired resistance, and the wires 85 (those indicated by light lines) having little or no resistance. It is from these terminals that the charge is taken for the cautery, diagnostic and sinusoidal apparatus and this is accomplished as will now be described. Two arms 86 and 87, in electrical contact with each other, are pivoted at the center of the circle about which the terminals 1¹ to 20¹ are arranged. The arms 86 and 87 are freely movable about their pivot 88, the arm 86 being of a proper length to engage any one of the terminals 1¹ to 20¹, said terminals being spaced apart a proper distance to permit the arm to contact with one only at one time. The other arm 87 is shorter than the arm 86 and is adapted to contact with three terminals, numbered respectively 89, 91 and 92, arranged within the circle of contacts 1¹ to 20¹ as will be later described. The terminal 89 is connected with one of a pair of posts 93 to which it is intended the leads to the cautery apparatus may be fastened. The other terminal of this pair is connected by a wire 94 with the first coil of the series 82. It is intended that charge shall be supplied

to the cautery apparatus from any one of the terminals 2¹ to 12¹, both inclusive, to which are connected the series of low resistance coils 82, it being desirable that this 5 circuit shall have the least possible interposed resistance. It will be noted from the drawing that the coil 79 cannot be brought into this circuit, as it is cut out by connecting the wire 94 with the wire to the terminal 10 2¹. Connection between any of the coils of the series 83 in this cautery circuit is prevented by an operating or manipulating handle 95 upon the arm 87 which prevents passage of the arm 86, the arm 86 being 15 mounted on the pivot 88 above the arm 87.

The diagnostic apparatus is adapted to be connected to a pair of binding posts or their equivalent 96, one of which posts is connected to the wire 94 and the other by a wire 20 97 with the terminal 91. This terminal is positioned to permit the arm 86 to contact with any of the terminals 2¹ to 16¹, both inclusive, the manipulating handle 95 of the arm 87 preventing introduction of the coils 25 with the terminals 17¹, 18¹, 19¹ and 20¹.

The sinusoidal apparatus is adapted to be connected to a pair of binding posts 98, one of which is connected by a wire 99 with the front end of the coil 79 and the other by 30 a wire 101 with the terminal 92, this terminal being so arranged that the arm 86 may contact with any one of the terminals 1¹ to 20¹. It will be noted that the arrangement of binding posts and their connections bring 35 the coil 79 into operation only when the sinusoidal circuit is used, giving the sinusoidal circuit a variation in control of twenty steps, the least charge from which, that provided when the arm 86 engages the terminal 1¹, being supplied wholly by the coil 79. As the arm is moved successively from one terminal to the other until it reaches the terminal 20¹, the individual coils of the series 40 82 first come successively into operation 45 until the terminal 12¹ is reached, after which the individual coils of the series 83 come successively into play until the terminal 20¹ is reached, the movement of the arm from each terminal to the next succeeding bringing 50 one more coil into operation and thereby increasing the charge proportionately.

The connections in the cautery and diagnostic circuits, when the arm 86 is in contact with the terminal 1¹, deliver no charge 55 as the cautery and diagnostic circuits do not require the services of the coil 79 and consequently these circuits start with the terminal 2¹, the cautery circuit going only through the terminal 12¹ and bringing successively the coils of the series 82 into effective operation.

The diagnostic circuit starts with the terminal 2¹ and ends with the terminal 16¹, bringing successively into operation all of 60 65 the coils of series 82 and the first four coils

of series 83. Two stops 102 are provided to prevent disarrangement of the arms and malformation of the circuits.

The circuits provided for the various apparatus comprise the principal ones desired 70 by medical practitioners at the present time, and it will be manifest that each of these circuits is subject to a fine and accurate control of the charges for the various forms of apparatus desired. 75

It is thought that the invention and many of its attendant advantages will be understood from the foregoing description, and it will be apparent that various changes may be made in the form, construction and 80 arrangement of the parts without departing from the spirit and scope of the invention or sacrificing any of its material advantages, the form hereinbefore described being merely a preferred embodiment thereof. 85

We claim:

1. In an apparatus of the character described the combination of a transformer having a plurality of secondary coils connected to each other and to terminals arranged for engagement by a moving arm, a moving arm for engaging said terminals, sinusoidal, diagnostic and cautery circuits receiving current from said coils, said circuits being closed through a second moving 95 arm adapted to close only a single circuit at a time, said last mentioned arm determining the circuit closed and the first mentioned arm the number of coils effective on the circuit. 100

2. In an apparatus of the character described the combination of a transformer having a plurality of secondary coils connected to each other and to terminals arranged for engagement by a moving arm, a moving arm for engaging said terminals, sinusoidal, diagnostic and cautery circuits receiving current from said coils, said circuits being closed through a second moving 105 arm adapted to close only a single circuit at a time, said last mentioned arm determining the circuit closed and the first mentioned arm the number of coils effective on the circuit, and means for restraining the number of coils in said circuits to a predetermined 110 number in certain of said circuits less than the number of coils in the secondary winding of said transformers. 115

3. In an apparatus of the character described the combination of a transformer 120 having a plurality of secondary coils connected to each other and to terminals arranged for engagement by a moving arm, a moving arm for engaging said terminals, sinusoidal, diagnostic and cautery circuits 125 receiving current from said coils, said circuits being closed through a second moving arm adapted to close only a single circuit at a time, said last mentioned arm determining the circuit closed and the first mentioned 130

- arm the number of coils effective on the circuit, said arms being arranged to prevent inclusion of too great a number of coils in said circuit.
5. 4. In an apparatus of the character described the combination of a transformer having a plurality of secondary coils connected to each other and to terminals arranged for engagement by a moving arm, a 10 moving arm for engaging said terminals, sinusoidal, diagnostic and cautery circuits receiving current from said coils, said circuits being closed through a second moving arm adapted to close only a single circuit at 15 a time, said last mentioned arm determining the circuit closed and the first mentioned arm the number of coils effective on the circuit, said arms having a common pivotal axis and being formed to prevent relative 20 passing to retain the arm engaging the terminals connected with the coils on a predetermined side of the circuit-determining arm to thereby prevent inclusion of too great a number of coils in certain circuits.
25. 5. In an apparatus of the character described the combination of a transformer having a plurality of coils of different electrical capacity, sinusoidal, diagnostic and cautery circuits including variable numbers 30 of said coils, and each circuit also including a pair of arms, one for determining the circuit operative and the other for determining the number of coils in said circuit, certain of
- 35 said coils being common to all of said circuits.
6. In an apparatus of the character described the combination of a transformer having a plurality of secondary coils, separately operable sinusoidal, diagnostic and cautery circuits including said coils and including also a pair of moving arms, one 40 for determining the circuit to be operated and the other to determine the number of coils in said circuit, and one of said circuits having supplemental secondary windings on 45 said transformer.
7. In an apparatus of the character described the combination of a transformer having a plurality of secondary coils, separately operable sinusoidal, diagnostic and 50 cautery circuits including said coils and including also a pair of moving arms, one for determining the circuit to be operated and the other to determine the number of coils in said circuit, and one of said circuits having supplemental secondary windings on 55 said transformer included in series with said plurality of coils.
